PLASTIC SHEET MATERIAL

John R. Ellefson, Newburgh, N.Y., assignor to E. I. du
Pont de Nemours and Company, Wilmington, Del., a
corporation of Delaware

Application January 15, 1959, Serial No. 54,179

Term of patent 14 years

(Cl. D87—3)

The figure is a plan view showing within the broken lines one complete repeating unit of my new design for plastic sheet material.

I claim:

The ornamental design for a plastic sheet material, substantially as shown.
